UNITED STATES PATENT OFFICE.

CHESTER VERSTEEG, OF ASHTON, SOUTH DAKOTA.

INDICATOR.

No. 848,519.

Specification of Letters Patent. Patented March 26, 1907.

Application filed November 14, 1906. Serial No. 343,386.

To all whom it may concern:

Be it known that I, CHESTER VERSTEEG, a citizen of the United States, and a resident of Ashton, in the county of Spink and State 5 of South Dakota, have invented certain new and useful Improvements in Indicators, of which the following is a specification.

My invention is an improvement in indicators for grain-bins, and consists in certain 10 novel constructions and combinations of parts hereinafter described and claimed.

Referring to the drawings forming a part hereof, Figure 1 is a perspective view of a bin provided with my improved indicators. 15 Fig. 2 is a vertical section through the swinging box and its supporting-plate, showing the parts in their normal position at the bottom of the bin. Fig. 3 is a similar view showing the position of the parts when the circuit 20 is closed. Fig. 4 is a diagrammatical view of a number of devices and the switchboard to which they are connected. Fig. 5 is a vertical section through the indicator, showing the parts in their normal position when 25 used at the top of the bin. Fig. 6 is a similar view showing the position of the parts when the circuit is closed, and Fig. 7 is a perspective view of the rod on which the box is mounted.

30 The present invention is an improvement over the device shown in Letters Patent No. 831,911, granted to me September 25, 1906, and comprising an open electric circuit, including a signal to be operated by the contact 35 of the terminals of the circuit, the said terminals being arranged within the bin in position to be moved into contact by the movement of the grain when it reaches a predetermined depth in the bin, and in means for 40 preventing the direct contact with the grain of the contact-points, while permitting their movement toward and from each other.

In the present embodiment of the invention a support A is arranged within the bin; 45 the support comprising a vertical portion a, provided with holes a², whereby it may be secured to the side of the bin by the screws a³ at any suitable point, and a horizontal portion a', provided with a threaded pin a⁵, on 50 which is a thumb-nut a^x, for a purpose to be hereinafter described.

A rod a⁶ is provided at one end with a flattened portion a⁷, having therethrough an opening through which extends the pin a⁵, 55 the rod being secured in its adjusted position with respect to the support by the thumb-

nut a^x before mentioned. At the opposite end of the rod a⁶ is provided a longitudinal slot a⁹ for receiving the reduced portion a¹¹ of a shield a¹⁰. The slot a⁹ extends to the end 60 of the rod, and a band a¹⁸ encircles the end of the rod whereby to securely clamp the slotted portion of the rod upon the reduced portion of the shield. The slotted end of the rod is provided with a threaded opening, in which 65 is engaged a screw a¹⁹, and a washer a²⁰ is arranged between the head of the screw and the end of the rod.

A closed box a¹³ is rotatably mounted upon the rod, and insulating material a⁸ is 70 arranged between the box and the rod whereby to insulate the said box from the rod. The box is slotted at its upper portion, as at a²¹, to permit the passage of the reduced portion a¹¹ of the shield, and the slot is sufficiently wide to permit the swinging of the box upon the rod without the edges of the slot contacting with the shield. 75

The box a¹³ is provided upon the inner face thereof with an insulating-plate a¹⁴, secured 80 to the box by any suitable means, as by the screws a¹⁵, and extending through the plate is a binding-post a¹⁶, the box being cut away around the binding-post, as shown more particularly in Fig. 1, whereby to insulate the 85 binding-post from the box.

The portion a¹² of the shield outside of the box is of approximately the width of the box, and the said portion a¹² arches over the top of the box and rod, as shown in Fig. 1, whereby 90 to deflect the running grain over the top and to each side of the box, the shield extending to approximately the bottom of the box.

Wires a²² a²³ are connected with the end of the rod a⁶ and with the binding-post a¹⁶, respectively, the wire a²² being arranged between the washer a²⁰ and the end of the rod and the wire a²³ being connected directly with the binding-post a¹⁶. 95

In practice an indicator may be arranged 100 in each bin at the bottom and at the top thereof, and the conductors from the indicators lead to a common switchboard arranged in some convenient part of the building. The switchboard B comprises a base b, having 105 arranged upon the face thereof a plurality of conducting-bars b' b², parallel with and spaced apart from each other, the ends of said bars being connected by the conductors b³ in an open current which includes a battery b⁵. 110 Between the contact-bars b' and b² are arranged a plurality of longitudinally-aligned

and spaced plates b^7 b^8 , the abutting ends of the plates being recessed, as at b^8 , for the reception of plugs b^9 , whereby to connect the plates with each other.

5 It will be evident from the drawings that the alternate plates b^8 are divided vertically by a strip of insulation b^{12} . The upper contact-bar b' is connected to an intermediate plate b^7 by conductors b^{13} . The wires a^{22} a^{23} , 10 leading from the rod and the binding post, respectively, are connected one with the contact-bar b^2 and the other with the plate b^8 , and a bell b^4 is interposed in each of the conductors. It will be evident from the description 15 that when the plugs are inserted in the openings the contact-points of each of the indicators 1, 2, 3, 4, and 5 are the terminals of an open circuit, which includes a bell and a battery. When the box of the indicator is 20 moved to bring its contact-point against the shield, the circuit is closed and the bell rings until the plug corresponding to the indicator is removed from the switchboard. The removal of the plug breaks the circuit and stops 25 the ringing of the bell.

It is obvious that a might bell be arranged in the circuit leading from the contact-bar to the battery or in the return-conductor, in which case all the indicators would have a 30 common bell, and drop-plates might be used in connection with the bell.

In operation the support A is placed in the bin in any suitable position, and the rod a^6 of the indicator is turned to bring it into the position shown at the upper part of Fig. 1 when the indicator is to be used at the top of the bin or to bring it into the position shown at the lower part of the said figure when it is to be used at the bottom of the bin, after which 40 the thumb-screw is made use of to secure the rod in its adjusted position. In either case the shield a^{12} is between the indicator and the side of the bin, whereby to prevent the grain accumulating directly between the box and the side of the bin. When the indicator is placed in the bottom of the bin in the position shown in Fig. 1, the grain in the bin moves the box into the position shown in Fig. 2, with the contact-point of the binding- 45 post out of contact with the reduced portion of the shield. When the bin is emptied and the grain is withdrawn from the front of the box, the box swings forward to the position shown in Fig. 3, thus completing the circuit 50 and ringing the bell. When placed at the top of the bin, the box normally stands in the position shown in Fig. 5 until the entering grain reaches a level sufficiently high to swing the box into the position shown in Fig. 55 60, when the circuit is completed, as before.

In filling the bin after the alarm is sounded enough grain may be run into the bin so as to entirely submerge the indicator before the flow can be stopped. If at any time grain 65 should be withdrawn from the bin sufficient

to relieve the pressure against the box, thus breaking the circuit, yet not enough to entirely clear the box, and under these conditions more wheat should be introduced into the bin, the wheat already between the box 70 and the wall would not permit the box to swing back as it should.

The shield permits the placing of the indicator close to the bin-wall, and since it is always close to the box but a small amount of grain 75 is permitted to enter between the box and the shield.

In Figs. 2 and 3 the reduced portion a^{11} of the shield is shown as bent slightly in order that the binding-post may contact with the 80 reduced portion when the box hangs vertically from the post, and the outer end of the binding-post is provided with insulating material which forms a stop between the binding-post and the body portion of the shield. 85

I claim—

1. An indicator for grain-bins comprising a support having a vertical portion for attachment to the wall of the bin, and a horizontal portion provided with a threaded post, a rod 90 having a flattened portion resting upon the horizontal portion of the support and provided with an opening through which passes the post, such rod being slotted at its opposite end, a thumb-screw engaging with the 95 post for securing the rod in its adjusted position, a closed box pivotally mounted upon the rod and insulated therefrom, a shield having a reduced portion passing through the slot of the rod and within the box, the portion 100 of the shield outside the box being arranged substantially parallel with the side thereof and spaced apart therefrom, said box depending normally substantially vertical from the rod, and being provided on its inner face 105 with a plate of insulating material having a binding-post for coacting with the reduced portion of the shield, an electric circuit having its terminals connected with the binding-post and with the reduced portion of the 110 shield respectively, said circuit including a signal operated by the contact of the binding-post with the reduced portion of the shield.

2. An indicator for grain-bins comprising a support arranged in the bin, a rod adjustably secured to the plate and having its free end slotted, a shield comprising a reduced portion passing through the slot of the rod, the body portion of the shield lying alongside the reduced portion and spaced apart therefrom, a 120 box mounted for rotation upon the rod and insulated therefrom, said box inclosing the reduced portion of the shield, a binding-post extending into the box and insulated therefrom, an electric circuit having its terminals 125 in the binding-post and in the reduced portion of the shield, respectively, and an electric circuit having a signal operated by the contact of the binding-post with said reduced portion of the shield. 130

3. An indicator for grain-bins comprising a support within the bin, a rod adjustably connected with the support, a box pivotally mounted on the rod and insulated therefrom, 5 a shield having a reduced portion within the box, the body portion of said shield lying outside of the box and spaced apart therefrom, a binding-post extending through the box and insulated therefrom, and an electric circuit having its terminals in the binding-post and the reduced portion of the shield, respectively, and including a signal operated by the contact of the binding-post with said reduced portion of the shield.

15 4. An indicator for grain-bins, comprising a box, a shield arranged alongside the box

and spaced apart therefrom, said shield having a reduced portion extending into the box, the box being movable with respect to said reduced portion, said box having a contact-point for coacting with the reduced portion of the shield, and an electric circuit having its terminals in the reduced portion of the shield and the contact-point of the box, respectively, said circuit including a signal operated by the contact of the contact-point and the shield.
